UNITED STATES PATENT OFFICE.

DAVID HUNTLEY, OF LONDON, ENGLAND.

ELECTRIC HEATING ELEMENT.

1,081,233.

Specification of Letters Patent.

Patented Dec. 9, 1913.

Application filed February 8, 1913. Serial No. 747,174.

To all whom it may concern:

Be it known that I, DAVID HUNTLEY, a subject of the King of England, and resident of London, England, have invented 5 certain new and useful Improvements in New or Improved Electric Heating Elements, of which the following is a specification.

The object of this invention is to produce 10 a strong, compact electric heating element, of simple construction, easily handled, readily replaceable, and in which the various parts may be removed with great facility and by persons of ordinary skill but without technical or electrical knowledge.

Heretofore mica and asbestos have been employed as insulators in combination with resistance wires, strips or tapes in the construction of electric heating elements, but 20 it has been found that when heated to a high temperature the mica or asbestos chemically affects the metal or alloy and produces more or less rapid oxidation, and a reduction of the sectional area of the wire, strip, or tape, and consequently sets up a greater resistance locally and ultimately causes the destruction of the metal. This is believed to be due to the presence of metallic or other substances in the mica or asbestos which produce chemical action when in contact with the metal or alloy, which action is increased by the presence of the electric current but it has been found that neither of these insulating materials used alone yield satisfactory 35 results. Other substances such as porcelain, glass, fireclay, quartz, or the like, have been employed for inclosing or supporting the resistance wires, strips, or tapes, but I prefer to use a combination of insulators and supports as hereinafter described.

Figure 1 of the accompanying drawings illustrates in front view an electric heating element constructed in accordance with my invention; Figs. 2 and 3 are longitudinal 45 edge and end views respectively of Fig. 1; Fig. 4 is a front elevation of a heating stove illustrating one application of my improved electric heating elements; and Fig. 5 is a side elevation of the same stove with the portion upon which the heating elements are mounted turned down for the purpose of examination or repairs.

Similar letters or reference relate to like parts in all the figures of the drawings.

Referring to Figs. 1, 2 and 3, *a* is the base 55 formed of fireclay for example, or of other

material of a refractory and highly electrical insulating character, in the face of which is molded or otherwise formed a recess *b* preferably of zigzag shape with rounded corners as shown, and extending from end to end of the base *a*. *c* is a helical wire coil of metal or alloy of relatively high resistance which is laid loosely into the recess *b*. *d* is a plain plate or slab of quartz or fused silica, preferably of the same length and width as the fireclay base *a* and arranged to cover the resistance coil *c*. In some cases the outer surface of the plate or slab *d* may be corrugated to form a greater surface for 60 radiation or broken up into any convenient pattern. The fireclay base *a* and the quartz plate or slab *d* are connected together at one or both ends by means of caps or clamps *e* which may be conveniently formed of sheet 65 brass or other metal bent or stamped into the shape shown and carrying terminal or contact screws *f* by which the ends of the resistance coils *c* are removably connected to the caps or clamps *e* for conducting the current into the said resistance coils *c*. Or such connection may be effected in any other suitable manner.

If desired more than one resistance coil *c* may be laid into the recess *b*, or instead of 75 such coils one or more strips of metal or alloy of relatively high resistance may be employed.

I sometimes inclose the back portion of the fireclay base *a* in a metal or other closed 80 casing or jacket *g* (Fig. 3) with a space *h* between, thereby preventing too rapid radiation of the heat from the back of the fireclay portion *a* of the element. And when it is desired to carry off the heat, openings 85 may be left at the top and bottom of the casing or jacket *g*, thereby allowing for the circulation of the air.

The metal caps or clamps *e* are preferably provided with a flange *i* by which any desired number of elements may be readily connected to a metal conductor plate by means of screwed studs *j* and wing-nuts *k* (Figs. 4 and 5) or by other suitable devices. And in order to retain the quartz plate or 100 slab *d* firmly in place, one or more portions of the caps or clamps *e* may be slit, as shown at *m* for example, and bent inward so as to bear upon the quartz plate or slab *d* with a more or less yielding or resilient pressure.

These completed elements may be employed for a great variety of purposes, such 105

as electric radiators, electric ovens, or other electric cooking or heating appliances, their shape and simple construction enabling them to be applied in a very easy and effective manner. For example, they may be made to form horizontal luminous bars in an electric radiator stove, and they may be provided with bent or corrugated reflecting surfaces at the back thereof, so as to assist or increase the circulation of the air, and reflect the heat rays. Such an electric radiator stove is illustrated in Figs. 4 and 5 in which four elements constructed as hereinbefore described with reference to Figs. 1, 2 and 3 are shown mounted in a horizontal position (by means of the wing-nuts *k*) upon vertically disposed conductor plates *n* which are attached by screws *o* and nuts *p* to the base plate *q* from which they are electrically insulated by means of the washers *r*. The base plate *q* is mounted upon the back plate *s* of the stove at a suitable distance therefrom as shown, and the said back plate *s* is hinge-jointed at *t* to the fixed portion *u* of the stove so that it may be turned down into the position shown in Fig. 5 for examination or repairs, or be turned up into the closed or working position and retained therein by the turn-buttton *v*. *w* are bent plates of black planished steel or the like attached to the base plate *q* between the elements so as to give the appearance more or less of the bars of an open fire grate.

The conducting wires may be so arranged

in relation to the switches *x* that the whole or part of the elements may be switched on or off according to requirement.

In Figs. 4 and 5 the heated air chamber *h* is separated from the backs of the elements by the base plate *q*, but it is obvious that portions of the said plate may be so cut and bent as to inclose the sides of each element, so that the back surfaces of the fireclay bases *a* would themselves form portions of the wall of the heated air chamber *h*.

The casing is covered at the front by a mesh screen or grating *A*.

Having now fully described my said invention, what I claim and desire to secure by Letters Patent, is:

In an electric radiator stove, the combination with a casing, of a member hinged therein, a base plate carried by said member, a plurality of bars upon said base plate and projecting upwardly therefrom, a series of conducting units removably mounted upon the base plate between the said upwardly projecting bars and insulated from the base plate and the bars, means for securing said conduction units to the base plate and means for controlling the electric supply.

In testimony whereof I have hereunto set my hand in presence of two witnesses.

DAVID HUNTLEY.
